FENCE POST

Edward J. Paque, Cincinnati, Ohio, assignor to
The Pollak Steel Company, Cincinnati, Ohio, a
corporation of Ohio

Application December 18, 1931, Serial No. 581,891

3 Claims. (Cl. 189—29)

This invention relates to improvements in fence post anchors and has for its object to provide an anchor formed from a single piece of sheet metal and adapted to be attached to the post in such a manner that it becomes the permanent part of the post.

It is also an object of this invention to provide a post anchor composed of sheet metal, on one end of which there is an entrance point, while at the other end there is a plurality of laterally disposed barbs to prevent the removal of the post from the earth in which it is buried. Intermediate these end parts, the anchor plate has struck up thereon cleats by which it is attached to the post.

It is also the object of this invention to provide an anchor plate adapted to be easily inserted with the post into the soil and retained therein by means of pointed structure at one end of the plate. This plate has the central part thereof deformed to form holding cleats for gripping the edges of the post. The post may also be welded to the plate at the points where the plate is deformed or adjacent the deformed parts of the plate.

It is particularly the object of this invention to provide an anchor plate for use in connection with the T-shaped posts adapted to receive one of the parts of the post and hold it in position in the soil. The other part of the post forms with the anchor plate means to prevent the removal of the post from the soil and also to prevent the rotation of the post in the soil.

An additional advantage of the post of my invention lies in the fact that the anchor plate is so formed as to increase the strength of the post assembly at the ground line, and the T-section is reinforced by means of the anchor plate, thereby remedying the weakest part of fence posts heretofore found in the art.

It is a further object to eliminate the use of rivets which weaken the construction as the rivet holes produce the cross-sectional area of the post near the ground line. The maximum strain is at or near the ground line when force is applied to the fence or fence post. The post of my invention is easily removed manually but resists movement due to frost heaving and loosening of the soil from natural causes, and from loads imposed during service.

These and other advantages will appear from the following description taken in connection with the drawings.

Referring to the drawings:

Fig. 1 is a front elevation of one form of post anchor with the anchor inverted.

Fig. 2 is a section on the line 2—2 of Fig. 1.

Fig. 3 is a view similar to Fig. 1 with the post inserted in the anchor plate.

Fig. 4 is a section similar to Fig. 2, showing the post attached to the anchor plate.

Fig. 5 is a front elevation of the anchor plate with the post attached thereto.

Fig. 6 is a section on the line 6—6 of Fig. 3.

Fig. 7 is a front elevation of a modified form of anchor plate.

Fig. 8 is a section on the line 8—8 of Fig. 7.

Fig. 9 is a view similar to Fig. 7 with the post attached to the plate.

Fig. 10 is a section similar to that shown in Fig. 8 with the post attached to the plate.

Fig. 11 is a front elevation of the plate and post as shown in Fig. 9.

Fig. 12 is a section on the line 12—12 of Fig. 9.

Fig. 13 is a front elevation of another form of anchor plate.

Fig. 14 is a section on the line 14—14 of Fig. 13.

Fig. 15 is a front elevation of the anchor plate shown in Fig. 13 with the post attached thereto.

Fig. 16 is a view showing a section of the plate similar to Fig. 14, with the post attached thereto.

Fig. 17 is a front view of the post and plate as shown in Fig. 15.

Fig. 18 is a section on the line 18—18 of Fig. 15.

Fig. 19 is a front view of another form of anchor plate.

Fig. 20 is a section on the line 20—20 of Fig. 19.

Fig. 21 is a rear elevation of the plate as shown in Fig. 19, with the post attached thereto.

Fig. 22 shows the section of the plate similar to that shown in Fig. 20, with the post attached thereto.

Fig. 23 is a section on the line 23—23 of Fig. 21.

Fig. 24 shows the side elevation of another form of anchor plate.

Fig. 25 is a section on the line 25—25 of Fig. 24.

Fig. 26 is a still another form of anchor plate.

Fig. 27 is a section on the line 27—27 of Fig. 26.

This invention relates generally to anchor plates formed of sheet metal with means integral therewith and formed as a part of the anchor plate for holding a post to the plate. In addition to the holding means, the plate may be welded to the post, and for cooperating with the plate, the post is formed of a T-shape with the cross part adjacent the anchor plate.

In each of the figures, the entrance end of the anchor plate is at the upper end as shown in the various figures, particularly Fig. 1. The anchor

plate shown in Figs. 1 to 6 is indicated by the numeral 1 and has therein a plurality of pairs of transverse slots 2.

The metal forming part of the anchor plate between each pair of slots is slotted and pressed up to form a pair of toes or cleats 3. These toes are arranged in pairs as shown in Fig. 1 and adapted to receive between them the lateral flanges of a T-shaped post with the central rib 10 part of the post projecting between the cleats or toe members.

One end of each plate is tapered as indicated by the numeral 4 to render the plate more easily forced into the ground for anchoring purposes.

15 The other end of the plate has formed on each side a lateral barb 5, by means of which the post attached to the plate and the plate are held in the ground or soil when they are once positioned in the soil.

20 The post is T-shaped and has laterally extending face plate parts 6 which constitute the laterally extending parts of the T-shaped post extending longitudinally. Intermediate the edges of the parts 6 is a longitudinal rib 7 which has on its outer edge the series of notches 8. In the present instance, these notches are arcuate in shape and assist in maintaining the post and the anchor plate in the soil. The longitudinal rib assists the anchor plate in preventing the rotation of the post.

25 In order to prevent the post from being withdrawn from the anchor plate, it is welded to the anchor plate at various points indicated by the numeral 9. As indicated in Fig. 4, the welds are located at the edges of the slots 2. The welds may be at any suitable convenient place.

30 In the form shown in Figs. 7 to 12, the plate is indicated by the numeral 10 and has a plurality of cross crimps 12 therein. By means of these cross crimps a plurality of parts 11 is formed in alignment with each other, but out of alignment with the main body of the plate so that a part of the post may be inserted between the parts 11 and the main body of the post before it is thus distorted.

35 Those parts of the plate uniting the parts 11 therewith are indicated by the numeral 12. In each part 12 there is a transverse slot 13. These slots are in pairs, with each pair connected by means of a slot 14. The slots 13 provide space for the reception of the laterally extending flanges of a T-shaped post, while the slots 14 receive the longitudinally extending rib of the post.

40 The plate has the usual tapered entrance end 15 and the lateral barb 16 on the opposite end.

The face plate or laterally extending parts of the post is indicated by the numeral 17, and has extending therefrom the longitudinally disposed rib 18 which has in its edge the plurality of 45 notches 19 to assist the plate in holding the post in the soil. These plates are held to the post by means of welding as indicated by the numeral 20.

45 This form of anchor plate is composed of one piece of sheet metal with all the necessary structural elements formed therein.

50 In Figs. 13 to 18, another form of anchor plate 21 is shown. This anchor plate has a plurality of oppositely disposed cleats 22 formed by transverse and longitudinal slits in the anchor plate. 70 After these slits have been made, the parts of the anchor plate adjacent the longitudinal slits are pressed up to form the cleats. The entrance point at one end of this plate is indicated by the numeral 23, while the lateral barbs at the other 75 end of the plate are indicated by the numeral 24.

The laterally extending parts of the post are indicated by the numeral 25 and have the usual longitudinally extending rib 26, with notches 27 in the free edge thereof. This post is held to the plate by means of welds 28 as clearly shown in Fig. 16.

80 Another form of anchor plate is shown in Figs. 19 to 22. In this form, the plate is indicated by the numeral 29 and has on one face struck up plate parts 31 and on the other face it has struck up parts 30, forming toes or cleats and cooperating with the parts 31 to grip the post. These parts 30 and 31 are separate from each other in the formation of the post by means of transverse slits. After these slits are made, the plate is still

85 in a flat condition. Those parts of the plate, forming the toes, are slit longitudinally and are pressed up as clearly shown in Fig. 22. The plate parts 31 are pressed in an opposite direction and, when thus pressed, cooperate with the toes or cleats in holding the lateral edges of a post when the anchor plate is slipped over the post. By this means, there is formed in the plate a groove 90 32 in which the face plate or lateral flanges 33 of the post fit.

The rib of this post is indicated by the numeral 34 and is of the same general form and shape as the other ribs and has on its free edge notches 35.

95 This plate is welded to the post as indicated by the numeral 36. The entrance end of this plate is indicated by the numeral 37, while the barbs on the other end of the plate are indicated by the numeral 38.

100 In Fig. 24 another form of anchor plate 39 is shown, in which the central longitudinal part of the plate is rolled to form a trough 40 which receives the laterally extending parts of the post 41. This anchor plate is welded to the post at the points indicated by the numeral 42. The rolling may be hot rolled or some other equivalent means. Usually anchor plates are formed cold, but the anchor plate of Fig. 27 would be hot 105 rolled.

110 In Fig. 26 another form of anchor plate 43 is shown, which has a pair of longitudinally extending parallel ribs 44 formed integral with the body of the plate between these ribs. The laterally extending parts of the post 45 are located therebetween and welded thereto at a point indicated by the numeral 46. This post has the longitudinally 115 disposed central rib 47.

120 These anchor plates are formed from one piece of sheet metal and may be formed by one single operation and after so formed are slipped over a T-shaped post. After the anchor plates are 125 suitably positioned on the posts, they are welded thereto at suitable points so that the plates become attached to the posts. The entrance end of each plate is adjacent the entrance end of the post and both are shaped so that the post may be readily inserted into the ground. They are also shaped to cooperate with each other to prevent the removal of the post and also to prevent the rotation of the post.

130 The removal of the post is prevented by means of the barbs and also by means of the notches on the longitudinal rib of each post. This longitudinal rib assists the lateral edges of the plate in preventing the rotation of the post so that in fact the post becomes substantially rigid and 135 can be only removed from the soil with difficulty.

I desire to comprehend within my invention such modifications as may be clearly embraced within my claims and the scope of my invention.

140 Having thus fully described my invention, what 150

I claim as new and desire to secure by Letters Patent, is:

1. In a fence post, an anchor plate therefor consisting of a plate having cross crimps therein forming parts in alignment with each other and out of alignment with the main body of the plate, said plate thus shaped being slotted to receive the post.

5 2. In a fence post, an anchor plate therefor consisting of a plate having cross crimps therein

forming parts in alignment with each other and out of alignment with the main body of the plate, said plate thus shaped being slotted to receive the post.

3. In a fence post, an anchor plate therefor consisting of a plate having cross crimps therein forming parts in alignment with each other and out of alignment with the main body of the plate, the cross crimps having slots therein to receive the fence post.

EDWARD J. PAQUE.
